UNITED STATES PATENT OFFICE

2,206,361

FUEL METERING DISTRIBUTOR

Frederick B. MacKay, Ashland, Mass.

Application April 14, 1938, Serial No. 202,097

1 Claim. (Cl. 137—145)

This invention relates to improvements in fuel metering distributors, and more particularly to a device of this type which will be driven from the cam or crank shaft of an internal combustion engine, and will efficiently distribute the fuel injected to the various cylinders of a multiple cylinder internal combustion engine.

An object of my invention is to provide an improved fuel metering distributor for internal combustion engines, which will be driven from the cam shaft or crank shaft of an internal combustion engine, and which will be provided with separate metering valves connecting the distributor with the several cylinders of an internal combustion engine, together with means for adjusting the valves to obtain the highest efficiency of fuel distribution to the said engine.

A further object of my invention is to provide an improved fuel metering distributor driven from the cam shaft or crank shaft of an internal combustion engine, and provided with a plurality of fuel metering valves having cooperating spring tensioned valve seats, and cam operated means for adjusting the said valves, whereby the fuel being injected to the several cylinders of the internal combustion engine may be efficiently accomplished.

A still further object of the invention is to provide an improved fuel metering distributor having a fuel inlet from a high pressure pump, and a plurality of radially extending distributing valves cooperating with adjacent spring pressed valve seats, having connection with the fuel inlet of the distributor, and being operatively connected with a vertically adjustable cam and a vertically adjustable drive sleeve splined to the cam, whereby the several metering valves may be efficiently operated.

A still further object of my invention is to provide an improved fuel metering distributor for injecting fuel into the various cylinders of a multi-cylinder engine, which will be highly efficient in operation, and quite inexpensive to manufacture.

Other objects will appear as the description proceeds.

In the accompanying drawings which form a part of my application,

Figure 1 is a vertical sectional view taken through my improved fuel metering distributor;

Figure 2 is a plan view taken on the line 2—2 of Figure 1;

Figure 3 is a side elevation of the splined drive sleeve; and

Figure 4 is a side elevation of the improved rotary cam.

Like characters of reference are used throughout the following specification and the accompanying drawings to designate corresponding parts.

In the construction of my improved fuel metering distributor, I provide a cylindrical housing 1, and a cap plate 2 or closure, supported upon the upper end of the housing 1 in fixed position by means of the bolts 3. Positioned upon the lower end of the cylindrical housing 1, I have provided a conical base or supporting head 4, which is secured in fixed position on the cylindrical housing 1 by means of the bolts 5, and the housing with attached cap plate and base are supported upon any desired member 6, for example a portion of an internal combustion engine, by means of the securing bolt 7.

Fuel from a high pressure pump, will be fed to the fuel metering distributor through an inlet pipe 8, which is secured by means of the threaded bushing 9 to the cap plate 2, and through the same. An annular fuel ring groove 10 is formed in the upper surface of the cylindrical housing 1.

Arranged about the cylindrical housing 1 at approximately ninety degrees apart, I have provided four fuel discharge outlets 12, which are connected by means of the threaded bushings 13 with the feed pipes 14 to the various cylinders 30 of a four cylinder internal combustion engine. The drawings show my invention built to operate with a four cylinder engine, although it is to be understood that the construction may be changed so that it will operate with engines having any desired number of cylinders.

Positioned within the four fuel discharge outlets 12, I have provided the radially extending needle valves 15, which are slidably mounted within the said outlets, and cooperate with the valve seat disks 16, which are normally forced into engagement with the annular shoulders 17 by means of the coiled springs 18, said needle valves, valve seat disks and coiled springs all being located within the radial discharge outlets. Vertically disposed fuel passages 19 connect the fuel ring groove 10 with the several fuel discharge outlets, and are controlled by the said needle valves and spring pressed valve seat disks.

The ball bearing races 20 and 21 are disposed in the upper and lower top plate and base member respectively, and provide a bearing for the vertically disposed driving shaft 22, which carries the gear 23 at its lower end, which may be operated or driven from the cam shaft or crank

shaft of the engine. An operating lever 29 is pivoted on the pin 30, and is connected to the lower end of the cam drive sleeve 24 by means of the slotted yoke member which cooperates 5 with the trunnions 33 carried by the ring 31, the trunnions operating in the slots 32 of the yoke lever 29 and are adapted to engage a thrust collar 34 on the lower end of said cam driving sleeve 24. A drive pin 35 will extend through 10 the upper end of the drive shaft 22 and will extend into the cam slots 27 and 28 in the splined cam drive sleeve 24, whereby the sleeve may be adjusted vertically by raising and lowering the operating lever 29.

15 Disposed upon the cam drive sleeve 24 and splined thereto, I have provided a rotary cam 36, which is cylindrical and is revolved through its center. On one segment of the outer surface of the cam 36, I have provided a depressed 20 portion or cam groove 37 which provides an injection curve consistent with proper combustion of injected fuel. This depression or cam groove 37 is of variable width in the vertical plane, as shown in Figure 4 of the drawings, and also in 25 Figure 1 of the drawings, in order to provide a means of metering the amount of fuel injection. The cam 36 may be moved in a vertical plane by means of the operating lever 38 pivoted on the pin 39 in the housing 1, in such a manner 30 that the inner ends of the needle valves 15 will ride in the cam grooves, to control the movement of the said valves to effect the metering of the fuel injected. It will of course be understood that suitable means not shown will be provided for 35 holding the levers 29 and 38 in their positions of adjustment. In normal operation the meter valves 15 will be seated upon the valve seats or disks 16 until the inner ends of the meter valves engage the cam groove 37, at which time the 40 valves are opened and the fuel is permitted to pass through the valves and out through the feed pipes 14. The connection between the yoke member 38 and the lower end of the cam 36 is made through the trunnions 42 carried by the 45 ring 40 and operating in the slots 43 in the yoke lever 38. A thrust collar 41 is threaded onto the lower end of the cam sleeve 36 and contacts the trunnion ring 40.

From the foregoing description, it will be apparent 50 that I have provided a fuel metering distributor for distributing the fuel to an engine, which includes dual metering means controlled by the operating levers 29 and 38, whereby ac-

curate metering may be had to meet the various requirements in the operation of the engine equipped with my improved fuel metering distributor. It might be further stated that by operating the lever 29, the cam 36 may be rotated 5 in a clockwise or anti-clockwise direction to regulate the timing of the valves 15.

While I have illustrated the fuel metering distributor as made for a four cylinder engine, it will be understood that the distributor may be changed so as to operate with an engine having any desired number of cylinders, and while I have described and illustrated one form of fuel metering distributor, it will be understood that I do not intend to limit myself to this particular 15 form of distributor as many minor changes in detail of construction may be resorted to without departure from the spirit of the invention. While I have illustrated and described one form of adjustable cam for operating the metering 20 valve, it will be understood that I may equally well employ a cam having a raised lobe of variable dwell, cooperating with various types of valves.

Having thus described my invention what I claim as new and desire to secure by Letters 25 Patent of the United States is:

In a fuel metering device, a housing, fuel passageways in the housing, discharge outlets communicating with the fuel passageways and having enlarged portions, needle valves extending into the enlarged portions of the fuel passageways controlling the flow of fuel through said fuel passageways, an operating shaft extending into the housing, a cylindrical cam on said shaft and movable therewith, said cam being mounted 35 for movement longitudinally of said shaft and having a cam groove extending inwardly from one end thereof, said cam groove being wide at its outer end and narrowing towards its inner end, said cam groove being in a line with the 40 inner ends of the needle valves, said valves being arranged to move with respect to the surface of the groove as the shaft rotates, allowing movement of the valves to unseat the valves whereby fuel may pass through said valves and means 45 for adjusting the cam longitudinally of the shaft, whereby a wide or a narrow portion of the groove is brought into alignment with said needle valves, regulating the action of the needle valves and controlling the passage of fuel through said body 50 portion.

FREDERICK B. MACKAY.
